DESIGN FOR AN OPERATING KNOB FOR AN ELECTRIC CONTROLLING DEVICE

Clifford Brooks Stevens, Milwaukee, Wis., assignor
to Cutler-Hammer, Inc., Milwaukee, Wis., a
corporation of Delaware

Application January 14, 1938, Serial No. 74,296

Term of patent 14 years

To whom it may concern:

Be it known that I, Clifford Brooks Stevens, a citizen of the United States and a resident of Milwaukee, in the county of Milwaukee and State of Wisconsin, have invented a new, original, and ornamental Design for an Operating Knob for an Electric Controlling Device, of which the following is a specification, reference being had to the accompanying drawing, forming part thereof.

Figure 1 is a top plan view of an operating

knob for an electric controlling device incorporating my new design.

Fig. 2 is a side elevational view thereof, and Figs. 3 and 4 are front and rear elevational views, respectively, of said operating knob.

I claim:

The ornamental design for an operating knob for an electric controlling device, substantially as shown.

CLIFFORD BROOKS STEVENS.
